(57) **CLAIM**

The ornamental design for a bird feeder, as shown and described.

DESCRIPTION

FIG. 1 is a perspective view of the bird feeder according to the present invention;

FIG. 2 is a front view of the bird feeder according to the present invention with the access lid in a closed position. The rear view is identical to the front view;

FIG. 3 is a right side view of the bird feeder according to the present invention with the access lid in an open position. The left side view is identical to the right side view;

FIG. 4 is a right side view of the bird feeder according to the present invention with the access lid in the closed position;

FIG. 5 is a top view of the bird feeder according to the present invention; and,

FIG. 6 is a bottom view of the bird feeder according to the present invention.

The broken lines shown in all views represent environmental structure and form no part of the claimed design.

The break in the chain is understood to represent indeterminate length.
